UNITED STATES PATENT OFFICE.

ABRAM GATES, OF CARROLL COUNTY, NEAR BURNETTS CREEK, INDIANA.

SPARK-PLUG.

1,337,216.

Specification of Letters Patent. Patented Apr. 20, 1920.

Application filed April 15, 1919. Serial No. 290,130.

To all whom it may concern:

Be it known that I, ABRAM GATES, a citizen of the United States of America, residing in the county of Carroll near Burnetts Creek, State of Indiana, have invented certain new and useful Improvements in Spark-Plugs, of which the following is a specification, reference being had therein to the accompanying drawing.

10 The invention relates to spark plugs and has for its object to provide a spark plug especially adapted for use in internal combustion engines, also to so construct the plug that the electrodes will be protected from 15 carbon deposits caused by the combustion of gases in the combustion chamber of internal combustion engines, and also free from oil.

20 A further object of the invention is to provide a spark plug mounted in a body member, said body member being provided with a downwardly extending ogival shaped housing arching over the electrode, said housing being provided with diametrically disposed elongated slots the upper ends of 25 which are at an obtuse angle to the vertical center line of the spark plug and to provide the lower end of the chamber of the housing with a convexed upwardly extending surface, which surface forms one of the arcing 30 points for the current.

35 A further object is to provide a spark plug wherein the electrodes are covered with an ogival shaped housing, said housing being provided with a chamber having an upwardly extending convexed lug, said convex lug allowing the initial explosion to pass downwardly into the combustion chamber of the engine and radially through vertical slots in the housing and to angle the upper 40 ends of said slots, whereby the initial explosion will be allowed to pass through the slots and into engagement with the upper end and surface of the cylinder, thereby getting the maximum ignition at the upper end 45 of the cylinder.

With the above and other objects in view, the invention resides in the combination and arrangement of parts as hereinafter set forth, shown in the drawings, described and 50 claimed, it being understood that changes in the precise embodiment of the invention may be made within the scope of what is

claimed without departing from the spirit of the invention.

In the drawings:

Figure 1 is a perspective view of the spark plug.

Fig. 2 is a side elevation of the same.

Fig. 3 is a vertical sectional view taken on line 3—3 of Fig. 2.

Fig. 4 is a vertical sectional view taken at right angle to Fig. 3 and showing the lock nut and body portion in section.

Fig. 5 is a sectional horizontal view through the housing, taken on line 5—5 of Fig. 2.

Referring to the drawings the numeral 1 designates the body of the spark plug, which comprises the hexagonal shaped portion 2 adapted to receive a wrench when the plug 70 is being screwed into the cylinder of an internal combustion engine and the integral downwardly extending ogival shaped housing 3 having a chamber 4 therein of the same shape as the outer surface of the housing. The portion 2 of the body member is provided with an internally threaded opening 5, in the bottom of which opening a copper washer 6 is disposed. Vertically and centrally disposed in the opening 5 is a 75 cylindrically shaped porcelain member 7, which is provided with an annular flange 8 adapted to rest upon the copper washer 6, this flange being of less diameter than the opening 5. Telescopically fitting the porcelain member 7 and threaded into the opening 5 is a lock nut 9 having a hexagonal flange 10 for the reception of a wrench, whereby the flange 8 may be forced into close engagement with the copper washer 6. 80 The lower end of the lock nut 9 being provided with an annular channel 11, which receives the upper edge of the flange 8, which channel 11 insures the centrally positioning of the porcelain member 7. Embedded in 85 the porcelain member is an electrode 12, the lower end of which extends downwardly through the lower tapered end 13² of the member 7 and is disposed over and in a near position to a convex upwardly extending lug 13, which forms the other electrode. The upper end of the electrode 12 terminates in a binding post 14 for the reception of a wire 90 through which electric energy is carried to

the electrode 12. The wall of the housing 3 is provided with vertically disposed elongated openings 15, which openings are preferably diametrically arranged. Each opening extends from the convexed surface of the lug 13 and has its upper ends beveled as at 16, which beveled surfaces 16 allow the flashes from the electrodes to pass upwardly into engagement with the upper surface of the engine cylinder as well as radially, as the flashes pass through the elongated openings 15. The outer surface of the housing is provided with threads 17, which are adapted to be threaded into a cylinder of an engine, these threads being so positioned that they will fit various kinds of engines.

By forming the housing ogival shaped, it will be seen that the maximum of length is obtained for the elongated slots 15, therefore the maximum of efficiency, at the same time it will be seen that when the charge is exploded in the combustion chamber, the ogival shape of the housing between the slots will protect the electrodes from collecting carbon. The convex apex of the housing protects the electrodes from the bottom, thereby preventing the entrance of carbon on the same. The ogival shape also presents a surface that is of such a shape that carbon will not easily collect on the same, and one wherein carbon that may collect on the same, will be easily dislodged, by the force of the succeeding explosions.

The convex lug 13, which forms one of the electrodes presents a wide range with which the end of the electrode 12 may be adjusted. It is common in spark plugs for the porcelain to not be true in shape, especially the flange 8 thereof. When this happens to be the case, the setting up on the

nut 9 will cause the lower end of the electrode 12, to be forced out of axial alinement with the body member 1, consequently out of vertical registration with the electrode 45 carried by the body member. In the construction of the kind shown this is not possible, nor is the exact alinement of the electrode 12 essential, for the reason that the convex surface of the lug 13 will allow the 50 arcing from any point on its surface. The convexed surface of the lug 13 also allows the flash from the electrodes to extend radially downwardly, thereby allowing the flashes to reach the combustion charge at 55 the sides of the cylinder.

The invention having been set forth what is claimed as new and useful is:—

A spark plug comprising a casing, said casing having an ogival shaped housing at 60 its lower end, said housing having an ogival shaped chamber therein, an insulated electrode disposed in said casing and having its lower end in said ogival chamber, a convexed upwardly extending lug in the apex 65 end of the housing chamber and forming an electrode adapted to coöperate with the first named electrode, and radially disposed slots in the ogival shaped housing, the lower ends of said slots being formed by the convexed surface of the convex lug thereby forming downwardly extending surfaces at the lower ends of the slot substantially vertically disposed so that the flash will enter the chamber radially in a horizontal plane 70 and downwardly in a substantially vertical plane and the upper ends of the slots terminating above the arcing points of the electrodes.

In testimony whereof I hereunto affix my 50 signature.

ABRAM GATES.
